Primary Examiner — George D. Kirschbaum*Assistant Examiner* — Lillian Windham(74) *Attorney, Agent, or Firm* — Van Court & Aldridge LLP(57) **CLAIM**

The ornamental design for an electronic tracking device, as shown and described.

DESCRIPTION

FIG. 1 is a bottom, front, left side perspective view of an electronic tracking device according to my new design;
FIG. 2 is a bottom, rear, left side perspective view thereof;
FIG. 3 is a front view thereof;
FIG. 4 is a rear view thereof;
FIG. 5 is a left side view thereof;
FIG. 6 is a right side view thereof;
FIG. 7 is a top view thereof; and,
FIG. 8 is a bottom view thereof.
The broken line showing is included for the purpose of illustrating portions of the electronic tracking device and forms no part of the claimed design.
